SLIDER SKATE

Charles E. Jones, Chicago, and William G. Crowle, Berwyn, Ill., assignors to Manning Manufacturing Corporation, Chicago, Ill., a corporation of Illinois

Application July 15, 1957, Serial No. 46,942

Term of patent 14 years

(Cl. D34—14)

Figure 1 is a perspective view of a slider skate showing my design;

Figure 2 is a top view thereof;

Figure 3 is a bottom view thereof;

Figure 4 is a side view thereof;

Figure 5 is a rear end view thereof;

Figure 6 is a front end view thereof.

The dominant portions of our design are shown in full lines, a portion of the broken line straps being omitted from Figs. 2, 3, 4 and 5 for convenience in illustration.

We claim:

The ornamental design for a slider skate, substantially as shown and described.
